UNITED STATES PATENT OFFICE.

ERNEST E. BROSS, OF DETROIT, MICHIGAN.

DESIGN FOR A FINGER RING.

Application filed January 5, 1924. Serial No. 8,254. Term of patent 14 years.

To all whom it may concern:

Be it known that I, ERNEST E. BROSS, a citizen of the United States, and a resident of Detroit, in the county of Wayne and State of Michigan, have invented a new, original, and ornamental Design for Finger Rings, of which the following is a specification, reference being had to the accompanying drawing, forming part thereof.

In the drawing, Figure 1 is a side eleva-

tion on a large scale of a finger ring embodying my new design. Figure 2 is a face elevation thereof on the same scale. Figures 3 and 4 are sections on the lines 3—3 and 4—4 of Figure 1, respectively.

I claim:

The ornamental design for a finger ring, as shown.

ERNEST E. BROSS.
